(57) **CLAIM**

The ornamental design for an audio controller, as shown and described.

DESCRIPTION

FIG. 1 is a front perspective view of an audio controller showing my new design;

FIG. 2 is another front perspective view thereof;

FIG. 3 is a rear perspective view thereof;

FIG. 4 is another rear perspective view thereof;

FIG. 5 is a top plan view thereof;

FIG. 6 is another top plan view thereof;

FIG. 7 is a bottom plan view thereof;

FIG. 8 is a front elevation view thereof;

FIG. 9 is a rear elevation view thereof;

FIG. 10 is a left side elevation view thereof; and,

FIG. 11 is a right side elevation view thereof.

The broken lines depict portions of the audio controller in which the design is embodied that form no part of the claimed design.

1 Claim, 10 Drawing Sheets
